APPARATUS FOR CHARGING FURNACES

Application filed January 23, 1932. Serial No. 588,310.

This invention relates to a new and improved apparatus for charging furnaces, and more particularly to apparatus for charging blast furnaces or the like whereby the distribution of the charged material may be controlled.

In the usual type of blast furnace or the like, the charge is permitted to flow into the top of the furnace from a charging hopper by lowering a bell closing the bottom of the hopper. This causes the charge to flow over the bell and against the outer walls of the furnace. In furnaces having bells of usual proportions this results in a depression under the bell and in an uneven distribution of the material. The fine material normally remains adjacent the furnace wall while the coarser material rolls down into the depression under the bell. This segregation of material results in having areas in the furnace of different gas permeability so that the gases tend to channel rather than to flow evenly throughout the area of the stock, as is desirable for efficient furnace operation.

The present invention enables the furnace operator to selectively place materials comprising the charge either against the wall or in the center of the furnace. Materials of different size may be thus located as desired or the different elements which go to make up the charge may also be selectively distributed.

It is an object of the present invention to provide a new and improved furnace charging apparatus.

It is a further object to provide apparatus in which the charge may be selectively directed toward the sides or center of the furnace.

It is an additional object to provide a construction having separate bell sections which may be selectively operated jointly or individually.

It is also an object to provide a construction in which the charging hopper edge is designed to engage edges of both bell sections.

Other and further objects will appear as the description proceeds.

We have shown a preferred embodiment of our invention in the accompanying drawings, in which—

Figure 1 is a fragmentary section showing

our improved bell applied to a blast furnace, both bell sections being closed;

Figure 2 is a side elevation of the bell operating mechanism;

Figure 3 is a plan view of the structure shown in Figure 2;

Figure 4 is a view of the structure shown in Figure 2 as seen from the left;

Figure 5 is a sectional view on a reduced scale showing the small section of the large bell opened; and

Figure 6 is a view similar to Figure 5 but showing both bell sections opened.

Referring first to the construction as shown in Figure 1, the upper portion of a blast shell 11 is shown at 11, the furnace having the refractory lining 12 and the plates 13 protecting the stock line. The charging hopper 14 is supported by the shell 11 and in turn supports the receiving hopper 15. The lower opening in the charging hopper 14 is closed by the central section 16 of the large bell, which comprises also the larger outer section 17. The bell section 16 is carried by a universal joint 18 from the tubular supporting member 19. The bell section 16 is provided with the recessed edge 20 into which the upper edge 21 of the outer section 17 fits. The circular line of junction between the two bell sections is covered by the enlarged lower edge 22 of the hopper 14.

The outer bell section 17 is provided with the inwardly sloping skirts or hopper portion 23, the skirt being connected by cross ribs 24 to a small central bell portion 25. This portion 25 is connected by universal joint 26 to the bell rod 27. The bell rod 27 passes upwardly through the tubular bell rod 19 which supports the bell section 16.

The upper or small bell 28 closes the lower end of the receiving hopper 15. This bell 28 is supported by a tubular bell rod 29 through which the bell rods 19 and 27 pass.

Referring next to the operating mechanism as shown in Figures 2 to 4, the supporting framing 30 is carried above the furnace top in any desired manner. The tubular bell rod 29 of the upper small bell is carried by the rods 31 connected by chains 32 to the arcuate ends 33 of bell crank levers 34 which are sup-

ported from frame 30 by the pivots 35. These bell cranks are activated by cables 36 connected to any suitable source of power.

The tubular bell rod 19, connected to the 5 smaller large bell section 16, is connected at its upper end by rods 37 to the chains 38 which are connected to the arcuate end 39 of the bell crank 40. The long end of the bell crank 40 is connected by cable 41 to any suitable operating mechanism. The slotted link 42 is pivotally connected to the bell crank 41 at 43 and is formed with an elongated slot 44.

The bell rod 27, connected to the outer large bell section 17, is connected at its upper end 15 by chain 45 to the arcuate end 46 of the bell crank 47. The long arm of the bell crank 47 carries a pin 48 which operates in the slot 44 of link 42. The end of this bell crank 47 has a depressed portion 49 which receives a cross 20 pin 50 carried by the vertical arm 51 of an auxiliary bell crank lever 52. This bell crank lever 52 is provided with cable 53 by means of which it may be swung in the clockwise direction and has a weighted arm 54 25 which tends to swing it in the counterclockwise direction.

In the operation of the charging assembly, each load of material which reaches the top of 30 the furnace is first retained on the small bell 28 and afterward dumped through on to the main bell section 16 within the hopper 14 by action of the bell crank 34, links 33 and rod 29, the above being lowered to permit the 35 passage of stock and again raised to provide a resting place for subsequent loads of material and also to provide a gas seal.

After a sufficient number of loads of material have been placed on the bell section 16 within the hopper 14, this material is lowered 40 into the upper part of the furnace.

By the use of our improved construction, the discharge of stock into the furnace may be over the edge of the large bell section 17 or over the inner edge of the suspended skirt 45 23. Alternative means of dumping the large bell are provided whereby material may be discharged at either of these points.

If it is desired to discharge material about the large circle of the outer edge of the large 50 bell section 17, the cable 53 is actuated to swing the bell crank 52 in the clockwise direction against the effect of the counterweight 54 so as to release the cross pin 50 from the recessed end of the bell crank 47. When this 55 release has taken effect the only connection between the bell crank 47 and the bell crank 40 is by means of the slotted link 42. The cable 41 is then slackened off which permits both bell cranks 40 and 47 to swing in the 60 counterclockwise direction to lower the rod 19 of the inner section 16 and the bell rod 27 of the outer section 17, and the entire assembly of two bell sections moves together, the bell in this case acting as an ordinary bell as 65 shown in Figure 6.

A return to the former position is effected by a pull on the cable 41 which returns the bell cranks 40 and 47 to the position shown in Figure 2, after which cable 53 is slackened off so that the bearing pin 50 again engages the depressed end 46 of the bell crank 47. 70

In the event that it is desired to discharge a charge of material contained on the bell section 16 and within the hopper 14 through the outer section 17 and within the circle 75 formed by the inside limit of the skirt 23, the apparatus is operated in the following manner. The cable 41 is slackened and the central bell section 16 is lowered by means of the motion of the rods 37 and the tubular bell rod 19. The position of the bell rod 27 and its connecting linkage is not affected, the bell crank 47 being held in place by the pin 50 resting in recess 46 and being held by the arm 51 of the bell crank 52. The material contained within the hopper 14 therefore flows over the edge of the bell section 16 and into the hopper formed by the outer bell section 17 where it is projected downwardly and 80 inwardly over the edge of the skirt 23 toward the center of the furnace. 85

By means of the elements shown, it is accordingly possible to discharge material toward the periphery of the furnace shaft or to concentrate delivery of this material at 90 the middle. By a combination of the two methods, it is possible to obtain many combinations of materials and to distribute ore, coke, limestone and scrap in relations to each other, which are not possible to accomplish 95 by means of the ordinary bell. It is also possible to effect a segregation of coarse material and fine material so as to exercise a powerful influence on the currents of gas which are traveling upward within the furnace and to direct these currents of gas so that they may be distributed at will over the entire cross-section of the shaft or may be concentrated toward the middle of the shaft 100 or toward its periphery at will. 105

While we have shown one form of apparatus constructed according to our invention, this is to be understood as illustrative only, as the construction may be modified to meet varying conditions and requirements and we 115 contemplate such changes and modifications as come within the spirit and scope of the appended claims.

We claim:

1. In a shaft furnace, charging apparatus 120 comprising a charging hopper, a two-part bell closing the lower end of the hopper, said bell comprising an inner part and a ring shaped outer part, a bell rod and operating bell crank for each of said bell parts, and a slotted link connecting the two bell cranks for joint operation. 125

2. In a shaft furnace, charging apparatus 130 comprising a charging hopper, a two-part bell closing the lower end of the hopper, said

bell comprising an inner part and a ring shaped outer part, a bell rod and operating bell crank for each of said bell parts, and a link connecting the bell crank, the link being pivoted to the central part bell crank and having a slotted connection with the outer part bell crank.

3. In a shaft furnace, charging apparatus comprising a charging hopper, a two-part bell closing the lower end of the hopper, said bell comprising an inner part and a ring shaped outer part, a bell rod and operating bell crank for each of said bell parts, and a third bell crank having a part adapted to engage one of said bell cranks to prevent movement thereof.

4. In a shaft furnace, charging apparatus comprising a charging hopper, a two-part bell closing the lower end of the hopper, said bell comprising an inner part and a ring shaped outer part, a bell rod and operating bell crank for each of said bell parts, and a third bell crank having a part adapted to engage the outer part bell crank to prevent movement thereof.

5. In a shaft furnace, charging apparatus comprising a charging hopper, a two-part bell closing the lower end of the hopper, said bell comprising an inner part and a ring shaped outer part, a bell rod and operating bell crank for each of said bell parts, a link connecting the bell crank, the link being pivoted to the central part bell crank and having a slotted connection with the outer part bell crank, and a third bell crank having a part adapted to engage the outer part bell crank to prevent movement thereof.

Signed at Chicago, Illinois, this 19th day of January, 1932.

ARTHUR J. BOYNTON.
PAUL ZIMMERMANN.
